UNITED STATES PATENT OFFICE.

OSCAR E. BRANSKY AND FRANCIS M. ROGERS, OF WHITING, INDIANA, ASSIGNEES TO
STANDARD OIL COMPANY, OF WHITING, INDIANA, A CORPORATION OF INDIANA.

ART OF HANDLING HEAVY OIL RESIDUES.

No Drawing.

Application filed January 18, 1923. Serial No. 613,550.

This invention relates to improvements in the art of handling heavy residues resulting from substantially non-cracking distillation of crude asphalt bearing petroleum oils and particularly to those residual products resulting when such an oil, for example, of the character of mid-continent crude oil, is reduced to a bottom or residue of high flash and fire test, the distillation being conducted either with steam or under vacuum, so that substantially no cracking takes place. The process is particularly advantageous in connection with the residues from asphalt bearing crude oils amounting to 10 per cent or less of the original oil.

In accordance with the present invention, the residue of the character described is treated with a very light hydrocarbon oil product, such as naphtha (boiling point range 190 to 330° F.), hexane or other light product having an end boiling point within the gasoline boiling point range, and the mixture is then allowed to settle. Suitable proportions are, for example, 10 to 30 parts of a residue amounting to from 7 to 10 per cent of the original oil and 70 to 90 parts of naphtha. After settling for a suitable period, say 12 to 24 hours, the solution of the residue and naphtha is decanted from the settled asphaltines, which, after removal of any naphtha they may contain, may be utilized in the manufacture of asphaltic pitches and the like. Instead of removing the asphaltines by settling, it is readily apparent that the solution of pitch in naphtha may be subjected to centrifugal action, and the asphaltines thereby separated.

The naphtha solution of the residue, after removal of the asphaltines, may be subjected to a treatment with sulfuric acid, for example, of 66° Bé., this treatment being suitably carried out, for example, by treatment of the diluted oil with sulfuric acid, as described in the prior application of Francis M. Rogers, Serial No. 584,863, filed August 28, 1922. The treatment is carried out in accordance with the nature of the final product desired, the subsequent treatment being varied with the same end in view. Thus, after treatment with sulfuric acid the diluted oil may be filtered

through fuller's earth or other clarifying material, or may be chilled and settled for the removal of petrolatum, a very high flash point bright stock or cylinder stock being thereby produced.

A material particularly suited for use in connection with the above process is, for example, the residue of about 7 per cent produced from mid-continent crude oil by reduction by fire and steam and having a melting point of about 110° F. and a penetration of 77 (A. S. T. M. method). After removal of the asphaltines, in the manner described, the dilute oil remaining may be treated with from 1 to 1½ pounds of 66° Bé. sulfuric acid per gallon, the treatment being preferably carried out in two or three dumps with removal of sludge after each dump. The resulting sour oil may be washed and neutralized and subjected to filtration for the removal of petrolatum, if desired. The residual product, after removal of the naphtha, is found to have a flash point of above 500° F. The removal of naphtha is in all cases effected by the usual distillation procedure.

We claim:

1. The method of handling a crude oil residue obtained by distillation from asphalt bearing oil substantially without cracking which consists in substantially diluting the residue with a hydrocarbon oil having an end boiling point in the gasoline boiling point range, removing undissolved asphaltines and treating the remaining diluted oil with sulfuric acid.

2. The method of handling crude oil residue obtained by distillation from an asphalt bearing crude oil substantially without cracking which comprises the steps of substantially diluting the residue with a hydrocarbon oil having a boiling point in the gasoline boiling point range, and removing undissolved asphaltines therefrom.

3. The method of handling crude oil residue obtained by distillation substantially without cracking and representing not more than 10 per cent of the original crude oil which consists in substantially diluting residue with a hydrocarbon oil having an end boiling point in the gasoline boiling point

range, removing undissolved asphaltines from the resulting solution and subsequently removing the light hydrocarbon oil.

4. The method of handling a crude oil residue obtained by distillation substantially without cracking and representing not more than 10 per cent of the original crude oil, which consists in substantially diluting the

residue with naphtha, separating undissolved asphaltines from the solution, treating the resulting solution with sulfuric acid and subsequently separating the naphtha from the treated oil.

OSCAR E. BRANSKY.
FRANCIS M. ROGERS.
